UNITED STATES PATENT OFFICE

REGINALD BOYD WOODCOCK AND THOMAS AUBREY KESTELL, OF LEICESTER, ENGLAND,
ASSIGNORS TO UNITED SHOE MACHINERY CORPORATION, OF PATERSON, NEW
JERSEY, A CORPORATION OF NEW JERSEY

SKIVING MACHINE

Application filed April 23, 1929, Serial No. 357,515, and in Great Britain June 5, 1928.

This invention relates to skiving machines and is herein illustrated as embodied in a machine of the type shown in Letters Patent No. 1,103,928 granted July 21, 1914 upon an application filed in the names of Arthur Bates, Arthur Ernest Jerram and Joseph Gouldbourn.

In skiving machines of this type in which the skiving knife is fastened to one end of a rotary shaft it is customary to use as a clamping member a screw, the stem of which passes through a hole in the knife and is threaded into the shaft. In the removal and replacement of knives of this kind, there is considerable danger that the operator may cut his fingers. In order to obviate this possibility as well as to enable the operator to hold the knife firmly while the clamping screw or other fastening means is being tightened and loosened, the knife, according to one feature of the invention, is provided with means adapted to be engaged by a hand tool. In the illustrated machine, in which the knife is fastened to the upper end 25 of its shaft, there projects from the upper face of the knife a boss which is circular in outline and is undercut. It may, therefore, be firmly held between the two suitably shaped pivoted arms of a hand tool while 30 the clamping screw is being loosened, for example; and then, while still held by the hand tool, may be removed from the machine.

Skiving machines of the type referred to above comprise a substantially flat uninterrupted work table, a rotary knife having that portion of its cutting edge which is operative at any given instant projecting through a slot in the table, a feed roll located beneath the operative portion of the edge of the knife and a work guide and presser which projects above the table and cooperates with the feed roll. With such a machine it is possible to skive the continuous edge of an ornamented opening in the work by threading the work upon the presser and swinging the work in a closed path.

In order to facilitate the skiving of the edges of small openings, which require that the work be swung sharply during the skiv-

ing operation, there is provided, according to another feature of the invention, an improved work presser mounting. In the illustrated machine this mounting comprises a member having a thin edge upon which the presser is supported and about which it may be adjusted angularly. By this construction the usual pivot pin for the presser is dispensed with and more space provided close to the presser in which to swing the work.

It is necessary at times to remove and replace the feed roll; and it is desirable that such removal and replacement of the roll should be permitted without disturbing the adjustment of the roll. To this end, according to another feature of the invention, the feed roll and its mounting are supported upon a carrier which may readily be detached from the frame of the machine. In the illustrated construction this carrier takes the form of a slide which is mounted in a horizontal guideway in the frame of the machine, a stop screw being provided for ensuring that the slide, after having been removed from the machine, may be replaced exactly in its original position so that the adjustment of the feed roll is not disturbed.

These and other features of the invention including certain details of construction and combinations of parts will be described as embodied in an illustrated machine and pointed out in the appended claims.

Referring now to the accompanying drawings,

Fig. 1 is a front elevation, partly in section, of a machine in which the invention is embodied;

Fig. 2 is a plan view, partly in section, of part of the machine;

Fig. 3 is a detail sectional view, on an enlarged scale, showing the mounting of the skiving knife upon its shaft;

Fig. 4 is a plan view of a tool for use when removing the knife; and

Fig. 5 is an elevation showing one half of the tool.

Before proceeding to describe what is new, a brief description of the old construction will be given. The machine comprises a box-like frame having a substantially flat upper

surface. The knife 7, which is mounted at the upper end of the driving shaft 9, is of dished or spherical shape, and its cutting edge projects through a slot in the top of the frame, the work being held against a feed roll 11 by a work presser 13, and thus advanced to the rotating knife. The feed roll 11 is driven through universal joints from a shaft 15 and is mounted for swinging movement about a pivot 17 carried by a vertically adjustable block 91. A spring supported strut 19 engages the feed roll and holds it normally in the angular position shown; and by turning the nurled member 21, the normal angular position of the roll may be varied. The work is fed away from the observer as viewed in Fig. 1, with the margin of the work held down upon the feed roll by the work presser 13, said work presser having previously been adjusted to cause the leather to be skived at the desired angle. As thus far described the machine is or may be substantially the same as that of the patent referred to above, and no further description of the old construction will be given.

In the present machine the skiving knife 7 has rigid with it a hub 23 which is clamped to the upper end of its shaft 9 by a screw 25 threaded into the end of the shaft. The head of the screw has formed on its under or clamping face a spherical seating surface which engages a concave surface on a washer 27 which clamps the hub of the knife to the upper end of the tapered knife shaft. The spherical and concave faces ensure that the knife shall be clamped in proper position upon its shaft.

The hub of the knife 7 has formed in the centre of its upper face a circular boss 29, the outer wall of which is undercut, to receive a hand-tool (Figs. 4 and 5) which may be clamped to it to hold the knife while the binding screw 25 is being removed or replaced and by means of which the knife may readily be removed and replaced without danger of the operator being injured.

The hand tool comprises two arms 31, 33 pivoted together at their right-hand ends about a pivot pin 35. A locking pin 37, pivoted at 39 to the left-hand end of the arm 31, is adapted to swing into a slot in the left-hand end of the arm 33, and is threaded to receive a butterfly nut 41. The right-hand ends of the arms are enlarged; and, formed in each, is a recess semi-circular in outline and undercut, the recess in the arm 31 being shown at 43. The two semi-circular recesses in the arms are caused to embrace the boss 29 on the knife, after which the pin 37 is swung into the slot in the left-hand end of the arm 33, and the butterfly nut 41 is screwed up to cause the boss 29 to be firmly gripped. The hand tool has fixed in it a pin 45 which, when the tool is clamped on the knife, enters a hole in

the frame of the machine to prevent the tool and knife from rotating as the binding screw 25 is turned.

As has been stated above, one feature of the invention is a construction whereby the feed roll may be removed from and replaced in the machine without disturbing its adjustment. To this end the vertically adjustable block 91, which carries the pivot 17, and the strut 19 and its support are mounted upon a carrier 47 in the form of a bracket which has a horizontal tongue-and-groove connection 48 with the frame of the machine, such that the bracket may be slid to the left, as viewed in Fig. 1 and removed from the machine if desired. The bracket is clamped to the frame of the machine by a screw 49, the stem of the screw passing through a slot in the bracket and being threaded into the frame of the machine. The bracket may be adjusted laterally of the machine by a screw 53 threaded through an arm on the bracket 47 and engaging a face on the machine frame. After removal of the clamping screw 49 and disconnection of one of the universal joints between the feed roll and its driving shaft 15, the bracket 47 with the feed roll and its strut 19 and adjusting devices may be removed as a whole from the machine for the purpose of cleaning or changing the roll or for any other purpose and may be replaced in exactly the same position as before by re-engaging the tongue and groove 48 and sliding the bracket along until the positioning screw 53 in the bracket engages the face on the machine frame and then inserting and tightening the clamping screw 49.

The work presser 13 is mounted to pivot on a thin, rounded edge 55 provided at the upper end of a bar 57 fixed or formed on a plate 59 which has a downwardly projecting stem 61 adjustably mounted in the frame as hereinafter described. The work presser 13 at its upper end in the vicinity of the knife is made as thin and small as possible so that, if the edge of an opening of small radius in a work piece is to be skived, the work piece may be threaded over the work presser and turned about as desired without undue interference from the presser. The presser 13 at its upper end has fixed in it a small thin plate 63 which projects into a gash in the said knife edge at the upper end of the bar 57 to prevent the presser from moving in the direction of feed of the work on the thin edge 55 of the bar. The presser at its lower end has an extension which projects under an arcuate flange 65 formed on the bar 57 and concentric with the edge 55 at the upper end of the bar 57, said extension having threaded through it a thumb-screw 67 adapted to engage the flange 65, thus enabling the presser to be locked solidly in adjusted angular position about the thin edge 55. The presser may have on it an indicating mark arranged

to move past a scale on the flange 65 to indicate the angle at which the presser is set. The stem 61 on the plate 59 is supported in a carrier 69 and is threaded to receive a hand-nut 71, positioned between arms on the carrier, by rotation of which the plate 61 and presser 13 are adjusted bodily up or down. A spring 73 in the carrier bears against a shoulder on the stem and presses the nut upwardly against one of the arms on the carrier to prevent the nut from being accidentally rotated. The plate 61 has an extension 75 which is guided between the surface of the carrier 69 and a block 77 fixed to the carrier to prevent angular movement of the plate 61. The carrier 69 is pivoted on a vertical pivot 79 at the right-hand side of the machine so that it may be swung outwardly away from its operative position and carry with it the work-presser 13 and its associated parts (all still in their adjusted positions on the carrier) so that the feed roll 11 and its parts may be removed as above described. The carrier 69 is locked in closed position in contact with the frame of the machine by a hook-bolt 81 mounted in the carrier and passing through a slot in the frame of the machine.

Although the invention has been set forth as embodied in a particular machine, it should be understood that the invention is not limited in the scope of its application to the particular machine which has been shown and described.

Having thus described the invention, what we claim as new and desire to secure by Letters Patent of the United States is:

1. In a skiving machine, a shaft, a knife, and means for detachably fastening the knife to the shaft, said knife having a boss adapted to be engaged by a hand tool to facilitate removal and replacement of the knife.

2. In a skiving machine, a shaft, a knife, and means for detachably fastening the knife to the shaft, said knife having an undercut boss adapted to be engaged by a hand tool to facilitate removal and replacement of the knife.

3. In a skiving machine, a shaft, a knife, and means for detachably fastening the knife to the shaft, said knife having an undercut boss circular in outline adapted to be engaged by a hand tool to facilitate removal and replacement of the knife.

4. A machine of the class described having, in combination, a knife, a feed roll, a work presser, and a supporting member having a thin edge upon which the presser rests and about which it may be angularly adjusted.

5. A machine of the class described having, in combination, a knife, a feed roll, a presser, a supporting member having a thin edge upon which the presser rests and about which it may be angularly adjusted, and

means for holding it in adjusted position.

6. A machine of the class described having, in combination, a knife, a feed roll, a presser, and a supporting member having a thin edge upon which the presser rests and about which it may be angularly adjusted, the member being provided with an arcuate flange the center of curvature of which lies in the thin edge, and the presser being provided with means for engaging the flange to hold the presser in adjusted position.

7. A machine of the class described having, in combination, a knife, a feed roll, a work presser, a supporting member having a portion of small area upon which the presser rests but with which it is unconnected, and means for holding the presser in position upon the supporting member.

8. A machine of the class described having, in combination, a feed roll, a carrier for the feed roll detachably mounted in the frame of the machine, and means on the carrier adapted to engage the frame of the machine to facilitate accurate replacement of the carrier after removal thereof.

9. A machine of the class described having, in combination, a knife, a feed roll, mechanism for adjusting the feed roll, a carrier upon which the feed roll and its adjusting mechanism are mounted, and means for detachably mounting the carrier on the frame of the machine.

10. A machine of the class described having, in combination, a knife, a feed roll, mechanism for adjusting the feed roll, a carrier upon which the feed roll and its adjusting mechanism are mounted, means for detachably mounting the carrier on the frame of the machine, and means on the carrier adapted to engage the frame of the machine to ensure accurate replacement of the carrier after removal thereof.

11. A machine of the class described having, in combination, a knife, a feed roll, a carrier upon which the feed roll is pivoted, a member mounted upon and movable with respect to the carrier for adjusting the roll about its pivot, and means for detachably mounting the carrier upon the frame of the machine.

12. A machine of the class described having, in combination, a knife, a feed roll, a carrier upon which the feed roll is pivoted, a member mounted upon and movable with respect to the carrier for adjusting the roll about its pivot, means for detachably mounting the carrier upon the frame of the machine, and means on the carrier adapted to engage the frame of the machine to ensure accurate replacement of the carrier after removal thereof.

13. A machine of the class described having, in combination, a dished knife, a rotary shaft at the upper end of which the knife is mounted, a feed roll located beneath the

knife, a pivot for the roll, an adjustable block in which the pivot is mounted, an adjustable spring-pressed member for supporting the roll for yielding movement about the pivot, and a carrier for the block and the member, said carrier being slidably mounted in the frame of the machine.

14. A machine of the class described having, in combination, a dished knife, a rotary shaft at the upper end of which the knife is mounted, a feed roll located beneath the knife, a pivot for the roll, an adjustable block in which the pivot is mounted, an adjustable spring-pressed member for supporting the roll for yielding movement about the pivot, and a carrier for the block and the member, said carrier being detachable and slidably mounted in the frame of the machine.

15. A machine of the class described having, in combination, a knife, a feed roll, a work presser, a carrier upon which the work presser is adjustably mounted, means for mounting the presser carrier for swinging movement away from the knife and roll, and a feed roll carrier upon which the feed roll is adjustably mounted, said carrier being readily removable from and replaceable on the frame of the machine.

16. In a skiving machine a rotary shaft, a knife, and a screw for fastening the knife to the shaft, said knife having means adapted to be engaged by a hand tool while maintaining the screw accessible, whereby the knife and its shaft may be held from rotation while the screw is turned.

17. A machine of the class described having, in combination, a rotary knife, a feed roll for advancing the work to the knife in a substantially horizontal plane, a work presser, and a carrier for the work presser pivotally mounted about a vertical axis which lies outside said presser, and means located between the vertical axis and the presser for clamping the carrier to the frame of the machine with the work presser in operative position.

In testimony whereof we have signed our names to this specification.

REGINALD BOYD WOODCOCK.
